UNITED STATES PATENT OFFICE.

WALTER RICHMOND, OF MEMPHIS, TENNESSEE.

CENTRIFUGAL EMULSIFIER OR MIXER.

1,031,666.

Specification of Letters Patent.

Patented July 2, 1912.

Application filed April 1, 1912. Serial No. 687,890.

To all whom it may concern:

Be it known that I, WALTER RICHMOND, a citizen of the United States, residing at Memphis, in the county of Shelby and State 5 of Tennessee, have invented certain new and useful Improvements in Centrifugal Emulsifiers or Mixers, of which the following is a specification.

My invention relates to an apparatus for 10 mixing or emulsifying liquids, and is especially adapted to the mixing of liquids and soluble solids such as malted milk, in which it is somewhat difficult to effect a complete solution of the suspended flakes or crystals.

15 The agitators at present in use for mixing liquids usually consist of a rotary disk, either smooth or having notched edges, and in operation they merely impart a whirling motion to the liquid in a containing vessel.

20 Such devices may be employed to agitate or stir liquids such, for instance, as are used for beverages, but they are not adapted to liquids which must be emulsified and which require an entirely different treatment.

25 It is the object of my invention to provide an apparatus which will effect a combined centrifugal and cutting action upon the liquid, thereby causing suspended particles to be more readily taken into solution.

30 In order that my invention may be more fully understood, I will refer to the accompanying drawings, in which—

Figure 1 is a side elevation of an apparatus embodying my invention; Fig. 2 is a 35 cross-section of the centrifugal emulsifier on the line 2—2 of Fig. 1; Fig. 3 is a bottom plan view of the emulsifier; and Fig. 4 is a vertical section on line 4—4 of Fig. 3.

The emulsifier 1, is secured to the lower 40 end of a shaft 2, connected by the socket 3 and set-screw 3^a, to a suitable driving motor 4, preferably an electric motor, which may be bolted or suspended upon trunnions 5, in a yoke 6, carried by a post 8, which telescopes into a hollow standard 10, so that it 45 may be readily lifted to raise the centrifugal tool 1, clear of the vessel or container 12.

The particular construction of the motor and its support form no part of the present 50 invention, and are merely illustrated in the common conventional manner.

I have found that while a rapidly rotating disk, either smooth or notched, may be 55 employed to agitate liquids for the purpose of mixing the ingredients, or to whip cream, etc., yet such devices are not effective in

causing suspended solid particles to be taken into solution, since this requires something more than a mere agitation, whipping, or churning action.

One of the uses for which my present invention is especially adapted is the rapid emulsifying of malted milk. As is known, it is somewhat difficult to cause the hard flakes of this substance to enter into solution. I, therefore, provide an apparatus which sets up a circulatory motion throughout the liquid in the vessel or container, and then by a combined centrifugal and cutting action disintegrates the particles and brings 60 them into intimate relation with the liquid. My apparatus first separates the liquid into a large number of minute streams and forcibly expels them outwardly through narrow channels by centrifugal action and then 65 by a rapid cutting action of the outer edges of the channels, these streams are cut transversely, thereby subjecting the suspended particles to a succession of disintegrating impacts and at the same time bringing these 70 particles into contact with fresh portions of the liquid. This results in an exceedingly rapid emulsification of the contents of the vessel, the suspended particles being taken 75 completely into solution.

80 My preferred embodiment of this invention, as illustrated in the drawings, comprises a ring or annulus 14, provided with one or more series of apertures 15, which form channels for the liquid as it is ejected 85 by the action of the blades or partitions 16. The annulus may be secured to the shaft 2, by means of a spider 18, having a rim 19, fastened to the upper edge of the annulus, or it may be merely carried by the blades which 90 are secured to the shaft. The blades are wide enough to extend above and below the apertures 15, and may be the same width as the annulus. The short shaft or stem 2^a of the tool may be integral with the main shaft 95 100 2 or may be screwed or otherwise secured thereto.

In operation, after the vessel 12 has been filled with desired ingredients and placed upon the base between the guides or clamps 105 21, the motor 4 is set in operation, and the post 8 is lowered into the standard 10, until the tool 1, is in the position shown. As previously stated, my apparatus is especially adapted for use in emulsifying liquids or 110 hastening the action of liquids in dissolving suspended particles, such as flakes and crys-

tals, which are otherwise difficult to dissolve. Thus, by means of my present invention I am enabled to dissolve the flakes of malted milk with great rapidity, and they are usually taken into solution very slowly. The rapid revolution of the blades 16, which frequently reaches 10,000 revolutions per minute, causes the liquid within the compartments of the centrifugal tool to be ejected through the apertures, thereby setting up circulatory currents in the liquid, as indicated by the arrows. The currents pass upwardly and downwardly in opposite directions and return through the intermediate portion, entering the tool in opposing streams or currents, where they are again thrown outwardly by the action of the blades. The liquid will also partake of the rotary motion of the tool, and will form vortices about the axis of rotation. The blades 16, lie in planes parallel to the axis, and do not act upon the liquid by any propeller or screw action as in some types of churning and mixers, since this would defeat the very purpose of my apparatus, and this distinction should be carefully noted. By reason of the parallel position of the blades with respect to the axis, they are inert to produce any upward or downward movement of the liquid, and their action is solely to throw the liquid within the tool outward by centrifugal force, the currents in the vessel being set up by the displacement thus caused within the tool and by the motion of the streams issuing from the apertures 15, which are projected against the sides of the vessel. It will be observed that the action of my centrifugal tool is entirely different from prior mixing agitators or churning tools. In fact, my device would not operate as a churning apparatus.

The effectiveness of my centrifugal mixing tool or emulsifier, in causing suspended flakes or solid particles to pass quickly into solution, is due mainly to the cutting action of the walls and edges of the channels or apertures 15. When the liquid is thrown outwardly by the vertical blades 16, the liquid, with its suspended solids, is crowded inwardly against the edges of the apertures upon the inner side of the annulus 14, as shown for illustration in one section or compartment of Fig. 2, and these cutting edges assist in breaking up the flakes and solid particles. The most effective action of the tool, however, is caused by the cutting edges surrounding the channels or apertures upon the outer periphery of the annulus. As previously stated, the tool is rotated very rapidly, thereby causing the outer edges of the apertures to actually cut across or trans-

versely of the minute streams issuing from the apertures. The suspended particles are thereby rapidly disintegrated, and moreover these are continually brought into contact with fresh particles of the liquid. In other words, the suspended particles are first crowded in small streams past the edges of the apertures upon the inside of the annulus, then between the walls of the channels, and immediately upon emerging upon the outside they are cut transversely by the rapidly whirling outer edges surrounding the apertures in the outer wall of the annulus. The importance of these features will be appreciated by those skilled in this art.

I have described in detail the particular construction illustrated in the drawings for the purpose of disclosing an embodiment of my invention, but I am aware that changes may be made therein without departing from my invention as defined by the claims.

I claim:—

1. A centrifugal mixing tool or emulsifier, comprising a rotary shaft, imperforate radially disposed blades having the planes of their operating surfaces parallel with the axis of said shaft, and an annulus surrounding and secured to said blades and provided with a series of apertures.

2. A centrifugal mixing tool or emulsifier, comprising a rotary shaft, an annulus carried thereby having a series of apertures or channels in its wall, and means for causing liquid in which the tool is immersed to pass into the annulus from opposite directions and to be ejected outwardly through said apertures.

3. A centrifugal mixing tool or emulsifier, comprising a rotary stem or shaft, imperforate radially disposed blades having the planes of their operating surfaces parallel with the axis of said stem, and an annulus surrounding and secured to said blades and provided with a plurality of rows of apertures.

4. A centrifugal mixing tool or emulsifier, comprising a rotary stem or shaft, imperforate radially disposed blades having the planes of their operating surfaces parallel with the axis of said stem, an annulus surrounding and secured to said blades and provided with a series of apertures, and radial arms projecting from said stem and secured to the upper part of the annulus.

In testimony whereof I affix my signature, in presence of two witnesses.

WALTER RICHMOND.
